UNITED STATES PATENT OFFICE.

NILS PAULSEN, OF NEW YORK, N. Y.

DRAFTING INSTRUMENT.

1,191,725.

Specification of Letters Patent. Patented July 18, 1916.

Application filed August 9, 1915. Serial No. 44,545.

To all whom it may concern:

Be it known that I, NILS PAULSEN, a subject of the King of Norway, and a resident of the city of New York, borough of Manhattan, in the county and State of New York, have invented a new and Improved Drafting Instrument, of which the following is a full, clear, and exact description.

This invention relates to a drafting instrument, and has to deal more particularly with that class of instruments by which parallel lines can be simultaneously drawn.

The invention has for its general object to improve the construction of devices of the character referred to whereby straight or circular parallel lines may be simultaneously drawn, the instrument being of light and compact form and including a plurality of marking elements which are readily adjustable to and from operative position and capable of being set to make lines any desired distance apart.

A more specific object of the invention is the provision of an instrument consisting of a plurality of spaced parallel beams each having one or more adjustable marking devices for enabling parallel lines to be drawn, the marking devices being adjustable longitudinally of the beams for the proper spacing of the lines, and capable of being swung on their respective beams to one side or the other, so as to be out of the way when not needed.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views, Figure 1 is a sectional view on the line 1—1, Fig. 2, with portions broken away to show the details of construction; Fig. 2 is a plan view; Fig. 3 is a detail sectional view on the line 3—3, Fig. 2, drawn on a reduced scale; and Fig. 4 is a perspective view of the guide shoe adapted to be used when straight lines are to be drawn.

Referring to the drawing, 1 designates the central or main beam of the instrument, and 2 are the parallel beams disposed at opposite sides of the central beam 1. These

beams are kept in proper spaced and parallel relation by passing through openings 3 in cross bars 4. The beams are preferably made hollow so as to be light, and the ends 60 may be closed by screw plugs 5. On the beams are arranged marking devices 6, there being one or more on each beam. On the central beam is a guide or pivot element 7 applied to one end, and at the opposite 65 end is a steadyng device 8. The element 7 is in the form of a depending arm 9 having an apertured head 10 to fit the central beam 1, and projecting upwardly from the head is a handle 11 whereby the instrument can 70 be conveniently manipulated. In the lower end of the depending member 9 may be arranged a pivot needle 12, or a guide shoe 13 may be applied to this arm so that by this shoe sliding on a straight edge or the like 75 the instrument can be properly guided. The guiding and pivot element 7 is held fixedly in place by a set screw 14 in the head 10 binding on the beam 1. The steadyng element 8 is a depending member removably 80 clamped to the beam 1 and having at its bottom a ball or equivalent device 15 whereby it can slide readily over the surface on which lines are to be drawn.

The marking devices may be ruling pens, 85 pencil points or the like. In the present instance each marking device comprises a depending member 16 having at its top an apertured head 17 through which a beam extends, the fit being loose enough to permit 90 the marking device to slide longitudinally or to swing on the beam. In the head 17 is a set screw 18 which is adapted to bind on the beam, and, if desired, each beam may have a longitudinal groove 19 into which the 95 set screw engages when a marking device is in vertical or operative position. By loosening the set screw 18 a marking device can be swung to one side and held in such position by tightening the set screw 18, as will be 100 clearly understood from Fig. 3. The pen 20 of the marking device may be of any desired construction, but in the present illustration the butt 21 thereof has a socket 22 into which fits a stem 23 depending from the 105 member 16. The stem 23 is slidable in a bushing 24 screwed in the member 16, and on the upper end of this stem is a head 25 on which presses a helical compression spring 26 disposed in the member 16. This 110 spring causes the head 25 to frictionally engage the inner end of the bushing 24 so as to

form a sort of clutch for preventing the pen or marking device from turning during the use of the instrument, but the marking device can be readily turned by the operator 5 about the axis of the stem 23.

When the instrument is in the condition shown in Fig. 1, a plurality of concentric circles can be drawn and the radii of the circles may be varied by longitudinally 10 shifting the marking devices on their respective beams. In this use of the device a pivot needle acts as the center of the circles and the steadyng device 8 slides over the surface of the paper, thereby maintaining 15 the beams parallel with the surface on which the circles are drawn, so that all the marking devices used will be equally effective. When straight parallel lines are to be drawn the shoe 13, shown in Fig. 4, is applied to 20 the element 7.

From the foregoing description taken in connection with the accompanying drawing, the advantages of the construction and method of operation will be readily understood 25 by those skilled in the art to which the invention appertains, and while I have described the principle of operation, together with the device which I now consider to be the best embodiment thereof, I desire 30 to have it understood that the device shown is merely illustrative and that such changes may be made when desired as fall within the scope of the appended claims.

Although only one steadyng device is 35 shown, more than one may be employed, and they can be placed on any of the beams, as may be found desirable.

Having thus described my invention, I 40 claim as new and desire to secure by Letters Patent:

1. A portable drafting instrument adapted to bear on and move over the surface to be marked, comprising a plurality of beams, bars connecting the beams together in fixed

relation, and marking devices carried by the 45 beams, whereby a plurality of parallel lines can be drawn.

2. A portable drafting instrument adapted to bear on and move over the surface to be marked, comprising a plurality of beams, 50 bars connecting the beams together in fixed relation, and marking devices carried by the beams, whereby a plurality of parallel lines can be drawn, said marking devices being adjustable longitudinally of the respective 55 beams.

3. A drafting instrument comprising a plurality of beams, bars connecting the beams together in fixed relation, marking devices carried by the beams, whereby a plurality of parallel lines can be drawn, said marking devices being adjustable longitudinally of the respective beams, a guide member mounted on one of the beams at a point outwardly from the marking devices, and a 65 steadyng device mounted on one of the beams at the side of the marking devices opposite from the guide member.

4. A drafting instrument of the class described comprising a plurality of parallel 70 beams, bars extending transversely to and connected with the beams for holding them in fixed spaced relation, a guide member on the central beam, a steadyng member mounted on the central beam, marking devices adjustable longitudinally of the beams and adapted to be swung from a vertical operative position, and means for clamping 75 each marking device on its respective beam in its operative or inoperative position. 80

In testimony whereof I have signed my name to this specification in the presence of two subscribing witnesses.

NILS PAULSEN.
